Kingsley & Kingsley

UNITED STATES PATENT OFFICE.

CHARLES R. SCHOTT, OF NEW YORK, N. Y.

LIQUID-DISPENSING DEVICE.

Application filed April 26, 1927. Serial No. 186,620.

This invention relates to liquid dispensing devices and more especially to devices for use in lubricating the springs, chassis, and the like of an automobile.

5 Heretofore, it has been customary to sell spring lubricating oil and the like in containers of suitable size to be held in the hand and to furnish them with a nozzle to be attached to the container when it is desired 10 to apply the oil or the like. With such an arrangement it is not practical to oil those portions of the springs, spring shackles, and other parts arranged under the body of the car as the container cannot be arranged 15 above the nozzle because of the limited space between the part to be lubricated and the body of the car and no means are provided to force oil upwardly through the nozzle.

An object of this invention is a container 20 for lubricants or the like provided with means for dispensing the contents thereof by means of compressed air, which means serves as a handle for supporting the container and by means of which the stream of oil dispensed from the container may be directed 25 as desired.

According to this invention a tube is attached to the upper portion of the container and is provided with means to cooperate 30 with the chuck of an air hose or the fitting on a tire pump so that a stream of air may be directed therethrough. A finger-grip is mounted on the tube by means of which the end of the tube may be pressed into the 35 chuck of an air hose arranged in the palm of the operator's hand. A second tube extends into the container and has one end so arranged that the stream of air discharged from the first tube produces suction in the 40 second tube. A nozzle may be provided for directing the stream of air and liquid produced by the flow of air through the first tube.

The tubes and the nozzle may be connected 45 directly to the container or may be connected to a cap which may either be the original cap for the container or a cap provided to replace the original cap. In the event that the tubes and nozzle are directly attached to 50 the container the latter will have no cap but means are provided to vent the container. Likewise, the cap is provided with a vent. When it is desired to use devices of this character the chuck of the air hose is arranged in the palm of the hand and the end 55 of the first tube inserted therein. Sufficient

pressure to open the chuck is applied by means of the fingers around the grip. The container is supported by the tube and as it is not of much weight can easily be moved 60 about and easily arranged in proper position to direct a spray of liquid wherever desired. With such device the otherwise inaccessible parts of an automobile may be easily gotten at as the liquid stream may be 65 directed as desired. It constitutes a very handy and convenient device which can be used wherever compressed air is available and as the container is connected directly to the air tube there is no trouble with tubes 70 leading from the container to the air tube and the only thing that has to be looked out for is the air hose.

Other objects, novel features, and advantages of this invention will be apparent from 75 the following specification and accompanying drawing, wherein.

Fig. 1 is a perspective view of the device embodying the invention,

Fig. 2 is a longitudinal section through 80 such device, and,

Fig. 3 is a partial section of a modified form.

10 designates a preferably metal can or container which is provided with a neck 11, 85 the top of which is closed. Mounted on the top of the neck 11 is an air tube 12 having a threaded end 13 which may be inserted in the chuck of an air hose or to which may be screwed the air tube of a tire pump. 14 is 90 the chuck of an air hose and is shown in position to receive the end 13 of the tube 12. A finger-grip 15 is provided on the tube 12 by means of which the end 13 of the latter may be forced into the chuck 14 to open the 95 same and permit a stream of air to flow through the tube 12.

A second tube 16 extends from the top of the neck 11 into container 10, the end of this tube being adjacent the end of the air tube 12 so that the stream of air from the tube 12 is directed across the end of the tube 16 to produce suction therein. A ball check valve may be provided at the bottom of the tube 16 to prevent flow of liquid from the tube into the can 10. A nozzle 18 is threaded into a socket 19 attached to the neck 11 in alinement with the end of the tube 12. In the neck 11 is provided a vent hole 20 which is closed by a seal 21 or the like to be pulled off when the device is first put into use. The upper end of the tube 16 may be closed

by a soft metal seal which is to be cut off or otherwise removed at the same time as the seal 21 is removed. The container may be filled with liquid before the tube 16 is inserted and with the vent hole 20 open. The tube 16 may then be soldered to the container and sealed and the seal 21 applied over the vent hole 20. The vent hole 20 is sufficiently small that the can cannot be re-filled without mutilation.

This provides a practically non-refillable can for lubricating oil to be sprayed on the springs and other inaccessible parts of automobiles, liquid polish for automobile bodies, and for liquid for many other uses. It ensures delivery of the original contents to the purchaser and prevents the can from being refilled with other liquids without mutilation after the original contents have been dispensed. It also provides an easy and efficient device for applying liquids where desired, permits control of the application of the liquids and prevents waste by directing the liquid in a fine spray where desired with penetrating force.

In the modification disclosed in Fig. 3, the neck 11^a of the can 10^a is open and screw threaded to receive a cap. The air tube 12^a is mounted on a cap suitable to be received by the neck 10^a as is the suction tube 16^a. The tube 12^a is provided with a threaded end 13^a and a finger-grip 15^a, similar to those disclosed in the modification presented in Figs. 1 and 2. The directing nozzle is not shown in this modification although it may be provided if desired. The cap to which the tubes 12^a and 16^a are attached may be the original cap for the container or may be a cap to take the place of the original container. In the former event the tube 16^a is closed with a soft metal seal as described in connection with Figs. 1 and 2. The cap is designed with a portion to be punched out to form a vent.

45 Either modification may be used in con-

nection with an air hose, the chuck of which is held in the palm of the hand with the fingers overlying the grip or in connection with the air tube of a tire pump or the like. When thus held, the device may be easily 50 lifted and located adjacent the parts to be lubricated and the stream of liquid accurately directed. When used in connection with the chuck of an air hose, the stream of liquid may be controlled by the pressure applied to the finger grip. With such device the ordinarily inaccessible parts of an automobile may be easily, quickly and thoroughly located.

Although the above description of the device has had more to do with its use in connection with lubricants, it is apparent that it may be made use of in connection with any suitable or desired liquid.

What I claim as new and desire to secure by Letters Patent of the United States is:

1. A device of the character described comprising a closed unitary container having a pair of orifices normally closed by soft metal seals, a discharge tube depending from one orifice into said container and the other orifice providing a vent for the container and an air tube rigidly connected to said container at one end and positioned to direct a current of air across the liquid discharge orifice.

2. A device of the character described comprising a closed unitary container having a pair of orifices normally closed by soft metal seals, a discharge tube depending from one orifice into said container and the other orifice providing a vent for the container and a finger grip on said air tube by means of which the free end thereof may be brought into operative relationship to an air chuck and the container be lifted and moved to direct the discharged liquid.

In testimony whereof, I have signed my name to this specification.

CHARLES R. SCHOTT.
